UNITED STATES PATENT OFFICE.

JOHN W. HUNTER, OF WINFIELD, KANSAS.

REFRIGERATING DEVICE.

1,179,316.

Specification of Letters Patent.

Patented Apr. 11, 1916.

Application filed September 10, 1914. Serial No. 861,103.

To all whom it may concern:

Be it known that I, JOHN W. HUNTER, a citizen of the United States, residing at Winfield, in the county of Cowley and State 5 of Kansas, have invented certain new and useful Improvements in Refrigerating Devices; and I do declare the following to be a full, clear, and exact description of the invention, such as will enable others skilled in 10 the art to which it appertains to make and use the same.

My invention is an improved refrigerating device and has for its object to provide a contrivance of this general class including 15 a canopy or the like and means for supplying cold air into the same, thus allowing a person suffering from heat or fever to be greatly relieved, it being understood that the canopy is to be positioned above such person.

With the above and minor objects in view, the invention resides in certain novel features of construction and combination herein described and claimed and shown in the 20 drawings wherein:

Figure 1 is a vertical longitudinal section through a refrigerating device constructed in accordance with my invention; Fig. 2 is a horizontal section taken on the line 2—2 of Fig. 1; Fig. 3 is a perspective view of the 25 refrigerating device showing the application of the cooling tent or canopy thereto; Fig. 4 is a perspective view of the supporting structure employed for retaining the tent or canopy in operative position; Fig. 5 is an end elevation of the refrigerating device and the canopy supporting structure connected thereto, showing the canopy in 30 section and illustrating the manner in which the same is applied in cooling the body of an invalid or other person suffering from heat.

In the accompanying drawings, an upright rectangular casing 1 is shown having a lining 2 preferably of galvanized sheet metal, spaced inwardly from its numerous 35 walls, a packing 3 being disposed between said walls and the lining as is common with devices of this character. The top 4 of the casing 1 is provided with a hinged door 5 which is normally held in closed position by 40 means of a suitable latch 6, said door being here shown as provided with a handle 7 and with a nipple 8 which projects through said

cover and which is provided with a suitable form of shut off valve 9.

As most clearly seen in Fig. 2, the front 55 portion of the front of the casing 1 is also provided with a hinged door 10 which is normally held in closed position by a suitable latch 11.

Located in rear of the door 10 and remov- 60 ably supported upon cleats 17 which are secured to the end walls 18 of the casing 1, is an ice pan 19 which is here shown as formed of a wooden plate or board 20 having a sheet metal covering 21 on its lower side and a 65 similar covering 22 upon its upper side, the intermediate portion of the cover 22 being depressed as indicated at 23 whereby to provide means for receiving the drippings from the ice 24 which is positioned upon a perforated plate 25 having supporting flanges 26 resting upon the cover 22. Near one end, the depressed portion 23 of the plate 22 is provided with a sleeve 27 which depends through the plates 20 and 21 and which is 70 located, directly above a central opening 28 formed in the top of a cylindrical drip pan 29 and connected therewith by a drip tube 34, said pan resting upon the bottom 14 and being preferably held against shifting 80 therein by a transverse cleat 30 which rises from said bottom.

As most clearly seen in Fig. 1, the bottom 14 is provided with an opening 36 which is normally closed by a pivoted valve plate 85 37 having an operating handle 38, said plate being pivoted beneath said bottom. It will therefore be seen, that when the valve plate 37 is moved to close the opening 36 and the valve 9 stands in closed position, no air 90 whatever may enter the interior of the casing 1, thereby providing an extremely efficient refrigerating device.

The casing, as above described, is provided at its four corners with upright 95 guides 39 in which the reduced upper ends 40 of supporting legs 41 are slidably mounted, set screws 42 being provided whereby the casing may be rigidly supported upon its legs in any one of a number of vertically ad- 100 justed positions. The lower portions of the end walls 18 of said casing 1 are likewise provided with L-shaped brackets 43 through the horizontal arms of which pointed thumb

screws 44 are threaded to allow the casing 1 to be attached to a box or the like for cooling the interior thereof in a manner which need not be illustrated in the present application.

The casing is preferably of such size as to allow the same to be readily transported from place to place by means of the handle 7, the device becoming extremely useful for 10 use upon picnics and the like in which instance, shelves 35 may be employed for the purpose of supporting the edibles.

The device may be further employed for the purpose of preserving ice by placing 15 the entire casing in the ordinary ice receptacle of a refrigerator or ice-box removing the shelves 35, and positioning the pan 19 on cleats 17' near the bottom of said casing, whereupon the entire casing 1 may be 20 filled with ice, which, due to the construction of the casing 1, will be preserved to an appreciable extent, yet when the valves 9 and 37 are opened, air is allowed to pass through the nipple 8 and into the casing 1 25 where it now becomes extremely cold and drops through the opening 36 into the ice-box or refrigerator with which the casing 1 is employed. When the pan 19 is positioned upon the cleats 17' the pan 29 is removed 30 and the tube 34 is passed through the opening 36, said tube leading to the drip discharge of the ice-box.

As most clearly seen in Figs. 3, 4, and 5, the rear wall 45 of the casing 1 is provided 35 with an upright guide 46 near its lower end, said guide receiving an upright shank 47 formed on a horizontal rod 48 which is thereby removably attached to said casing, said rod extending rearwardly from the 40 guide 46 and having its free end bent upwardly and formed into an eye 49 through which a second horizontal rod 50 slides, said rod 50 having one of its ends turned downwardly and formed into an eye 51 embracing 45 the rod 48, whereby said rod 50 may be adjusted toward or away from the receptacle 1, a set screw 52 being preferably passed through the portion of the rod 48 forming the eye 49 for the purpose of locking 50 said rod 50 against movement. As most clearly seen in Fig. 4, the rear end portion of the rod 50 is bent downwardly at right angles as indicated at 52', is turned laterally as at 53 and then bent upon itself as at 54, 55 the free end of said rod projecting laterally in the opposite direction from the portion 53 as indicated at 55. By this formation, a supporting and bracing foot is provided at the lower end of the portion 52 of the rod 50. The construction just described, is employed 60 when the device is used for reducing the temperature of a person suffering from heat or fever, in which application the casing 1 is raised to the proper extent upon its

legs 41, said legs now straddling the body of 65 the invalid as indicated in Fig. 5. When in this position, the supporting structure, just described overlies the lower portion of the person's body with the supporting means at the lower end of the portion 52' resting 70 upon the bed cover C upon which the person lies. With the parts in this position, a tent or canopy 56 is positioned upon the device as clearly seen in Figs. 3 and 5, said canopy having an inverted V-shaped end 75 wall 57 which lies adjacent the portion 52' of the rod 50 and a pair of side walls 58 which extend longitudinally from the end wall 57 and contact with the end walls 18 of the receptacle 1, said walls 58 being then 80 continued as indicated at 59 in Fig. 5, to provide an opposite end wall whose lower end is slit as at 60 to receive the neck of the person whose body is thereby located beneath the canopy. The extended portions 85 59 of the side walls 58, constituting one end of the tent or canopy 56, are attached to an endless flexible band 61 which yieldingly embraces the casing 1 when the parts are in this position, one end portion of the walls 90 58 and the top 62 of the canopy being likewise attached to said flexible band 61. It will therefore be seen, that when the band 61 is stretched or expanded, the canopy 56 may be entirely removed from the casing 1 95 and the supporting means in rear thereof after which said supporting means may be removed from the guide 46.

When the canopy 56 is employed for the above set forth purpose, the valves 9 and 37 100 are opened, thus allowing cool air to pass into the interior of said canopy thereby effectually reducing the temperature of the patient's body. The drip pan 29 is used in this connection.

Having thus described my invention, what I claim as new and desire to secure by Letters Patent is:

1. A device for the purpose set forth comprising a refrigerating receptacle having air ports in its upper and lower ends, legs for supporting said refrigerating receptacle at the desired height, a supporting rod projecting laterally from one wall of said receptacle and a canopy surrounding 115 said receptacle and having a depending skirt, a portion of said canopy being supported by said laterally projecting rod.

2. A device of the character described comprising a refrigerating receptacle having air passages in its upper and lower ends an elastic band yieldingly encircling said receptacle, a canopy having portions connected with said flexible band, said canopy projecting laterally from said receptacle in 125 one direction, and means whereby said laterally projecting portion of the canopy may be supported.

3. A device of the character described comprising an upright refrigerating receptacle having air passages in its upper and lower ends an elastic band yieldingly enclosing said receptacle, a canopy having a portion secured to said elastic band depending therefrom, one portion of said canopy projecting laterally from said refrigerating receptacle, and means carried by the receptacle for supporting said laterally projecting portion. 5 in said guide, a canopy having a portion overlying said rod and having an opening near one end, and a flexible band secured to said canopy at the edges of its opening, said band encircling said receptacle. 30
4. A device of the character described comprising an upright refrigerating receptacle having air passages in its upper and lower ends a flexible band encircling said receptacle, a canopy having a rectangular opening in its upper side, the edges of said canopy adjacent said opening, being secured to said flexible band, a portion of said canopy projecting laterally from the refrigerating receptacle, and means carried by the receptacle whereby said laterally projecting portion may be supported. 15 20 25
5. A device of the character described comprising an upright refrigerating receptacle, a guide carried by one side thereof, a rod having a portion removably inserted 35 40 45

6. A device of the character described comprising an upright receptacle having a guide thereon, a rod having a portion removably inserted in said guide, said rod projecting laterally from said receptacle and having a guide on its free end, a second rod slideable in said last mentioned guide, a supporting standard depending from the second mentioned rod, means whereby said rods may be locked against movement, a canopy having its top overlying said rods, and having an opening in said top, and a band attached to said canopy at the edges of the opening therein, said band embracing said receptacle.

In testimony whereof I have hereunto set my hand in presence of two subscribing witnesses.

JOHN W. HUNTER.
